(57) **CLAIM**

The ornamental design for a medical tissue matrix forming compressor, as shown and described.

DESCRIPTION

FIG. 1 is a top, front, right side perspective view of a medical tissue matrix forming compressor, showing the new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a bottom, rear, left side perspective view thereof. The broken lines in the figures show portions of the medical tissue matrix forming compressor that form no part of the claimed design.

The dot-dashed line in the figures defines the boundary of claimed and unclaimed objects, and the dot-dashed line forms no part of the claimed design.
